UNITED STATES PATENT OFFICE.

ALEXANDER S. CAPEHART, OF BISMARCK, NORTH DAKOTA.

TYPE-LINE-CASTING MACHINE.

SPECIFICATION forming part of Letters Patent No. 579,298, dated March 23, 1897.

Application filed January 18, 1897. Serial No. 619,514. (No model.)

To all whom it may concern:

Be it known that I, ALEXANDER S. CAPEHART, a citizen of the United States, and a resident of Bismarck, North Dakota, have invented certain new and useful Improvements in Type-Line-Casting Machines, of which the following is a full, clear, and exact specification.

This invention relates to type-setting and line-casting machines of that class wherein lines of movable female type or matrices or lines of impressed matrices are presented to one side of a mold and molten metal introduced at the opposite side for the purpose of casting slugs or type-high printing-bars having at one of their edges relief-type the counterparts of the intaglio characters or of the impressed matrices. In machines of the character alluded to the casting mechanism usually comprises a casting-pot heated by the flame from a burner and having a plunger by which molten metal is forced through the mouth of the casting-pot into the mold.

The chief objects of my present invention are to avoid the presence of a flame for heating the casting-pot, which unduly heats surrounding or other parts of the machine; to maintain the metal in the casting-pot at the required temperature without unduly heating surrounding parts of the machine; to convey the molten metal from a receptacle or source of supply independent of, or separate from the line-casting machine to the casting-pot, by which it is properly delivered at predetermined intervals and in the required quantities into the mold; to maintain the metal in the proper molten condition in transit from the remote receptacle or source of supply to the casting-pot; to provide means whereby a single receptacle or source of supply may be utilized to supply molten metal at the proper temperature to the casting-pots of a group of line-casting machines; to render the line-casting machine less disagreeable to the operator, and to secure regularity in the product of the machine.

To accomplish the objects stated, I electrically heat the casting-pot of the line-casting machine and connect it, through the medium of an electrically-heated pipe, tube, or conduit, with a melting pot, receptacle, or vessel located more or less remote from and independ-

ent of the line-casting machine, and heated by electrical or any other desired means.

The construction and arrangement of the various parts for carrying my invention into effect may be widely varied, and therefore the illustration in the accompanying drawings is only designed as typical of many different constructions and arrangements that may be employed.

In the drawings, Figure 1 is a sectional side elevation showing my invention in operative connection with the mold of a monoline type setting and casting machine. Fig. 2 is a diagrammatical view indicating several line-casting machines having their casting-pots supplied according to my invention, and Fig. 3 is a detail view showing the preferred form of casting-pot.

I intend my invention for any type of line-casting machine having a mold and casting-pot for casting solid lines of type or type-high printing-bars bearing relief-characters at one edge which are the counterparts of lines of movable female type or lines of impressed intaglios presented to and closing one side of the mold. I have, however, illustrated my invention in connection with a casting-pot and a mold similar to those used in the monoline type setting and casting machine.

In the drawings, the numeral 1 indicates a casting-pot, 2 a mold, and 3 one of several matrix-bars assembled in line at the side of the mold opposite the side presented to the casting-pot. The casting-pot, which is arranged in operative connection with the mold, is preferably composed of a cylindrical casing containing a plunger 4 and constructed with a throat 5, rising from the lower end of the casting and provided with a perforated delivery-mouth 6 of a length coextensive with the length of the mold-cell in which the slug or type-high printing-bar is cast. The cylindrical casing is also constructed near its lower end with a lateral inlet-orifice 7, which in any suitable manner is placed in communication with a metallic pipe or tube 8, leading to and communicating with a melting pot or vessel 9, designed to be heated by the flame from a gas-burner 10 or by electrical means or otherwise. The melting-pot is isolated or located at a point remote from and is independent of the type-setting and line-casting machine,

and preferably the melting-pot is arranged at a higher level than the casting-pot in the machine, so that the molten metal will flow by gravity through the pipe or tube to the casting-pot.

The pipe or tube is electrically heated by properly coiling a naked wire conductor 12 thereupon and connecting the same with a dynamo or other source of electric fluid. The casting-pot is also heated by an electric conductor 13, coiled around the same and adapted to convey an electric current for heating the pot. The electric conductor for heating the pot may be a part of or it may be independent of the electric conductor for heating the pipe or tube leading to the melting-pot. The electrical appliances for heating the pipe or tube and the casting-pot may be of any construction and arrangement suitable for the purpose in hand, and therefore I wish it understood that my invention comprehends the electric heating of the pipe or tube and the casting-pot in any manner which will secure the desired results of maintaining the metal in the pipe or tube and the pot in a molten condition and avoiding the use of a flame from a gas or other burner in the line-casting machine.

The plunger 4 of the casting-pot serves to open and close communication between the pot and the pipe or tube through the orifice 7. When the plunger descends, the communication between the pot and the pipe or tube is closed, and the metal in the pot is displaced and forced through the throat 5 and delivery-mouth 6 into the mold-cell, where the printing-bar is cast. When the plunger ascends, the metal in the delivery-mouth and throat is drawn by suction toward the casting-pot, and the communication between the latter and the pipe or tube is established for supplying the pot with a quantity of metal substantially in proportion to the quantity which was delivered into the mold. The melting-pot is designed to communicate, through the medium of a plurality of electrically-heated pipes or tubes, with the casting-pots of a group of line-casting machines, whereby it is possible to supply all the casting-pots from a single vessel in which the metal is melted.

The casting-pot may in practice be made movable, so that its mouth may be moved up to the mold when the printing-bar is to be cast, or the mold may move up to the mouth of the casting-pot, or both parts may be made movable with relation to each other.

The casting-pot and the whole or a part of the pipe or tube are jacketed, as at 14, in any suitable manner with non-conducting material to prevent undue radiation of heat.

In Fig. 1 the cylinder of the casting-pot 1 is arranged within an outer cylinder around which the electric conductor or wire 13 is wound, and the whole is inclosed in a casing 15. This form of casing is similar to that used in the monoline-casting machine.

In Fig. 3 I illustrate the preferred form of casting-pot, wherein the electric heating-coil 13 is placed directly upon the cylinder in which the plunger 4 operates and extends along the throat 5 of the pot to a point in juxtaposition to the delivery-mouth 6. The casting-pot shown in Fig. 3 is designed to be jacketed with any suitable insulating material.

The delivery of the molten metal to a casting-pot having a force-pump or its equivalent and a delivery-mouth constructed to cooperate with a mold designed to cast a printing-bar or a solid line of relief-characters is important in that the casting-pot is constantly supplied and possesses the characteristics which are essential for the practicable production in a type-setting and line-casting machine of comparatively long slugs or printing-bars, each having at one edge a line of relief-type representing a line of composed matter for printing purposes.

It has heretofore been proposed to connect a type-casting mold with a melting-pot by an electrically-heated tube constructed at its delivery end with a fixed tapering nozzle arranged in operative connection with the mold to eject the metal directly thereinto to cast single type, but such construction is impracticable in connection with a type-setting and line-casting machine in that the fixed nozzle end of the tube cannot operate to produce a useful result with the mold used in such machines and cannot properly supply the requisite quantity of molten metal to a mold designed to cast a solid line of type representing composed matter.

My invention is particularly useful where the mouth of the casting-pot is of considerable length to cast comparatively long lines of type. In such case it is difficult to maintain the throat and its delivery-mouth at the required temperature, and this cannot be effected by ordinary means without unduly heating parts of the machine which it is desirable to avoid heating. If the metal flowing through the throat and its delivery-mouth is not properly heated, imperfect printing-bars are obtained because the metal is too cool when the casting is made.

The electric heating devices render it possible to maintain the required temperature at the throat and mouth of the casting-pot without unduly heating other parts of the machine and without the odor and other annoyances incident to ordinary methods of heating the casting-pot.

While I prefer to heat the casting-pot solely by electrical means, such as described and shown, I wish it understood that the pot may be heated partly by electrical means and partly by the flame from a burner. In such case the throat and mouth of the pot should be heated electrically. I consider, however, the heating partially by an electric current and partially by a gas or other burner undesirable and inferior.

I may wind the electric wires or conductors around the inside of the outer cylinder, Fig. 1, and around the outside of the inner cylinder or well and the outside of the throat and mouth.

Having thus described my invention, what I claim is—

1. The combination with the mold of a type-line-casting machine, constructed to cast a printing-bar bearing a line of relief-characters, of an electrically-heated casting-pot co-operating with the mold, means for causing metal to flow from the casting-pot into the mold, a melting-pot arranged remote from said casting-pot and independent of, or separate from the line-casting machine, and an electrically-heated conduit leading from the melting-pot and communicating with the casting-pot.
2. The combination with the mold of a type-line-casting machine, constructed to cast a printing-bar bearing a line of relief-characters, of an electrically-heated casting-pot co-operating with the mold and having a lateral orifice in its side, a melting-pot arranged remote from the casting-pot, an electrically-heated conduit leading from the melting-pot and connected with the lateral orifice of the casting-pot, and a plunger which passes said orifice and thereby opens and closes communication between said conduit and the casting-pot through said lateral orifice, and serves to force the metal to the mold.
3. The combination of a mold, a casting-pot

cooperating with the mold, a melting-pot arranged remote from the casting-pot and independent of, or separate from the line-casting machine, a conduit leading from the melting-pot and communicating with the casting-pot, and a plunger arranged in the casting-pot for displacing the metal therein and forcing it to flow into the mold.

4. The combination of a group of line-casting machines, having molds and electrically-heated casting-pots co-operating with the molds, with a melting-pot independent of, or separate from the line-casting machine and having a plurality of electrically-heated connections with the casting-pots of said line-casting machines.

5. The combination with the mold of a type-line-casting machine, of a casting-pot having an electric heating device applied about its throat which delivers the molten metal into the said mold, a melting-pot arranged remote from said casting-pot and independent of, or separate from the line-casting machine, and a conduit leading from the melting-pot to the casting-pot, substantially as and for the purposes described.

In testimony whereof I have hereunto set my hand in the presence of two subscribing witnesses.

ALEXANDER S. CAPEHART.
